UNITED STATES PATENT OFFICE

FRANK W. ANDREWS, OF FORT WAYNE, INDIANA, ASSIGNOR, BY MESNE ASSIGNMENTS, TO APEX ELECTRICAL MANUFACTURING COMPANY, OF CLEVELAND, OHIO, A CORPORATION OF OHIO

CAPILLARY MEANS FOR FORWARDING LUBRICANT FROM THE EVAPORATOR OF REFRIGERATING SYSTEMS

Application filed May 21, 1928. Serial No. 279,253.

My invention relates to refrigeration systems and particularly to those in which a sufficient quantity of lubricant is mixed with refrigerant when the system is charged and sealed, to effectually lubricate all moving parts where friction would cause wear.

This invention is limited to so-called flooded system refrigeration apparatus and particularly as applied to the boiler or evaporator of such apparatus; the broad invention being covered by my pending application on Method of and means for lubricating refrigeration systems, filed Mar. 19, 1928, Serial No. 262,815.

The liquid refrigerant in each boiler or evaporator should boil freely and the best practical condition in such a flooded system is attained when there is the smallest possible quantity of oil present in the boiler at any time. A large quantity of accumulated oil cools, and retards the evaporation of the refrigerant. Frequently, especially in multiple hookups such as shown in Fig. 1 an excessive accumulation of oil in the evaporator of one or more of the refrigerators causes those units to function more and more slowly and imperfectly and finally to cease functioning altogether. Sometimes in multiple hook-up installations when one or more refrigerators become oil logged there is not enough oil in circulation to properly lubricate the compressor, shaft seals squeak and bearings are ruined, necessitating shutting down the whole system, and putting all the refrigerators out of use, causing great inconvenience to each user.

My invention is illustrated in the accompanying drawings, in which:—

Figure 1 is a diagrammatic drawing of a compressor in the basement of an apartment house with two refrigerators on the first floor, and two on second floor, with liquid refrigerant supply and gas return pipes leading to other higher floors (not shown), the whole constituting a multiple hook-up flooded system of refrigeration such as is used in apartment buildings. Each refrigerator is equipped with a boiler or evaporator, cooling coil, etc., through which refrigerant is circu-

lated by and through the compressor in the basement;

Fig. 2 is an elevation of the ice chamber compartment at the upper right corner of a refrigerator with the evaporator and cooling coil secured in position; 55

Fig. 3 is a section on the line 3—3 of Fig. 2, the float and valve mechanism being shown in full and the liquid inlet valve closed;

Fig. 4 is a view of the boiler only, similar 60 to that of Fig. 3, and shows another form of valve lever secured to the float ball permitting a lower normal level and less quantity of the refrigerant in the boiler;

Fig. 5 is a vertical axial section through 65 the boiler and shows another form of the device;

Fig. 6 is a detail of the suction return vaporized refrigerant tube and attached oil forwarding means shown in Figs. 3 and 4, 70 said view being mostly in vertical, axial section.

Fig. 7 is a detail of the oil tube shown in Fig. 5, bent to avoid the valve mechanism below it; 75

Fig. 8 is a detail of the oil tube and return vaporized refrigerant tube shown in Fig. 5, said view being mostly in vertical axial section, and

Fig. 9 is an enlarged detail of the liquid 80 refrigerant receiver shown in Fig. 1, parts at the inlet and outlet being shown in vertical axial section.

Referring now to the drawings, and for the present particularly to Fig. 1 a compressor 1, driven by motor 2 by means of belt 3 has condenser coils 4, 4, connected to the compressor at 8, all mounted on base 5 which rests on the basement floor or any other convenient support, and carries the liquid receiver 6 into which the condenser coils 4 are connected at 7. 85

Refrigerant in gaseous form mixed with lubricant leaves the compressor under compression at 8, passes through condenser coils 95 4 where it is cooled and liquified in the usual manner by the fan fly-wheel 9 or otherwise and enters the liquid receiver 6 at 7. Refrigerant and some lubricant flow upwardly through the portion 11 of tube 10 at the left, 100

while lubricant also rises on the wick 12 at the right of tube 10 by capillary attraction and particles of lubricant are carried onward and upwardly with the refrigerant through liquid supply pipe 13 to the boilers or evaporators 14^a of refrigerator A 14^b of refrigerator B, 14^c of refrigerator C and 14^d of refrigerator D.

Referring now particularly to Figs. 2, 3, 10 and 4, and assuming that these mechanisms are shown installed in refrigerator A, the evaporator 14^a, its cooling coil 15 and attendant mechanism are all attached to what is usually called the ice compartment of the refrigerator A, by suspending bolts 16 and supporting strips 17 or in any convenient manner.

Within the evaporator 14^a is a needle valve 18 controlling the inlet 19 opened when float-ball 20 falls upon lowering of the level 20 of the body of liquid refrigerant and lubricant, and closed when the float-ball 20 rises to the point shown in Figs. 3, 4 and 5. The shape of the lever 30 may determine the 25 height of the body of refrigerant and lubricant in the evaporator at which the valve 18 closes. (See Figs. 3 and 4.) Gas passes through return suction vapor tube 21 in open communication with the outlet 22, with or 30 without baffle 23 underneath, and into this tube is connected preferably on the under side, a tube 24 with slot 28 and provided with a wick 25 or other means for conveying the lubricant upwardly by capillary attraction. 35 The wick is saturated with the lubricant before charging the system with refrigerant and preferably before insertion in the tube 24. An opening 26 is generally provided in the tube 21, and is usually designated as a 40 vent, oil inlet or bubble breaker. The tube 24 may be bent as shown in Fig. 7 where the outlet 22 is directly above the inlet 19, to avoid the valve 18 and attendant parts.

Another form of the device is shown in 45 Fig. 5 the upper ends of the tubes 21 and 24 being parallel and united by brazing or soldering with a slot 27 providing open communication between them and tube 24 closed at the top, and provided with the slot 28.

50 Referring again to Fig. 1 it will be understood that the liquid supply pipe 13 is connected to each of the inlets 19 and that each of the outlets 22 is connected through return pipe 29 with the suction side of compressor 1.

55 While I have shown and described the best forms of the invention known to me, I do not wish to be limited to these forms, but claim any apparatus using a wick or other capillary means to carry over the lubricant from 60 the evaporator of a refrigerating system of the flooded type toward the compressor as within the scope of my invention.

I claim as my invention and desire to secure by Letters Patent of the United States:—

65 1. In combination with the evaporator of

a refrigeration system of the flooded type through which lubricant is circulated with refrigerant, an outlet above the liquid level in said evaporator, and a wick extending from a place contiguous to said outlet and in the path of gaseous refrigerant normally flowing therethrough downwardly into the body of accumulated lubricant.

2. In combination with the evaporator of a refrigeration system of the flooded type 70 through which lubricant is circulated with refrigerant, an outlet above the liquid level in said evaporator, a perforated tube extending downwardly from a place contiguous to said outlet and in the path of refrigerant 75 flowing therethrough to the body of lubricant in said evaporator and a wick in said tube.

In testimony whereof I have hereunto set my hand.
